TRANSPORTATION OF CHEMICALS

Robert Burns MacMullin, Niagara Falls, N. Y.,
assignor to The Mathieson Alkali Works, Inc.,
New York, N. Y., a corporation of Virginia

Application September 20, 1939, Serial No. 295,716

5 Claims. (Cl. 23—293)

My invention relates to improvements in the transportation of caustic soda.

The caustic soda of commerce is ordinarily brought to a concentration of at least 50% NaOH at the point of production prior to shipment to the point of use. The transportation of lower concentrations would of course involve the handling of more water than caustic. The three concentrations generally available in commerce are 48%—52% NaOH, 65%—70% NaOH and 98%—100% NaOH.

The 50% NaOH caustic soda is an aqueous solution having a freezing point of about 50° F. At ordinary atmospheric temperatures caustic soda of this concentration has but slight corrosive action with respect to ordinary steel and it therefore can be shipped and handled in containers of ordinary steel for many purposes. For some purposes, however, nickel or nickel lined containers or containers protected with a film of an appropriate coating composition resistant to such corrosion must be used to prevent contamination with iron. But in any event a weight of water equal to the weight of NaOH must be transported when caustic soda is shipped as 50% NaOH doubling the cost of transportation per unit of NaOH.

The 70% caustic soda has a melting point of about 147° F. and is customarily charged into the shipping container as liquid at a temperature above its melting point. During shipment the caustic soda cools and may partially or even completely solidify unless inconvenient and expensive steps are taken to keep it at a temperature above the melting point, either by supplying heat or by insulation. To the extent that solidification occurs, it is necessary to remelt the 70% NaOH caustic soda in order to effect its discharge from the container upon delivery. The shipment and handling of caustic soda at 70% NaOH concentration has the advantage that 7 parts by weight of NaOH are transported for every 3 parts of water, but 70% NaOH caustic soda at temperatures above its melting point is quite corrosive with respect to iron and steel and, to a somewhat lesser extent, to nickel, and the corrosion resistant coating compounds sometimes used to protect steel containers against 50% NaOH caustic soda generally fail at the higher concentrations and higher temperatures involved in the transportation of 70% NaOH caustic soda. Moreover, any surfaces through which heat is transferred to the caustic soda must attain temperatures substantially exceeding the melting

point thus involving a corrosion problem of extreme difficulty.

Anhydrous caustic soda is usually shipped and handled either in solid masses or as a flaked or granulated product. The fused anhydrous caustic soda may be run into steel containers in which it is allowed to solidify or it may be flaked or granulated and then packed for shipment and handling in hermetically sealed steel containers. 10 The shipment and handling of caustic soda as the anhydrous product eliminates the useless transportation of water, but concentrations exceeding about 80%—85% NaOH cannot be attained in the ordinary vacuum evaporators so 15 that the final concentration is conventionally effected in directly-fired fusion pots and this fusion as ordinarily practiced involves such contamination of the product with metallic impurities that a supplemental, and expensive, finishing operation is required to eliminate impurities introduced into the caustic soda during the concentration. The containers in which anhydrous caustic soda is shipped and handled, moreover, 20 represent an added element of cost since they must ordinarily be discarded as of no further use upon delivery of the product.

The bulk of the caustic soda of commerce is ultimately used in concentrations substantially lower than 50% NaOH. For example, in the rayon industry, one of the larger users of caustic soda, the caustic soda is commonly used at a concentration of about 18% NaOH. Special requirements of the users of the caustic soda must be satisfied. In the rayon industry again, for 30 example, extreme purity with respect to iron and nickel and other heavy metals is required. Subject to such limitations, the user wishes to have the caustic soda delivered at the point of use for the lowest possible cost per unit of NaOH and the cost of transportation is an important 35 component of the final cost to the user. Other components of this final cost are the cost of production, the cost of concentration and the cost of any required finishing.

45 My invention provides improvements in the transportation of caustic soda which assist in reducing the final cost of this product to the user by reducing transportation costs and by achieving an advantageous balance between other costs involved such as concentration and finishing.

For several years I have experimented with the transportation of caustic soda at concentrations such that the product was solid at ordinary atmospheric temperatures in railway tank cars. 50 I have found that a satisfactory load of flaked

or granulated solid caustic soda could be charged into railway tank cars of conventional construction by providing a few additional small charging ports along the top of the tank. When I endeavored to discharge the tank thus charged by adding water to the caustic soda in the tank to reduce it to a concentration at which it would be liquid at ordinary atmospheric temperatures, however, I encountered difficulties which I had not anticipated. When water was run into a tank of caustic soda through the conventional ports provided on top of the tank, initial solution was rapidly followed by stratification of the water and of the liquor forming as the caustic soda dissolved which so reduced the average rate of solution that long and indefinite periods were required to bring the contents of the tank to a condition such that they could be conveniently discharged as a liquid. Also, the heat of solution of the caustic soda tended to involve local rises in temperature which in turn involved contamination with the metal of the tank or tank lining or destruction of protective coating compositions. I have now discovered however that, if water is added to the lower part of such a container thus charged with solid caustic soda containing about 65%-85% NaOH, the caustic soda dissolves very rapidly and without stratification or local overheating to form a solution conveniently and easily discharged from the container. To facilitate the rapid formation of a uniform solution of the caustic soda I may blow the contents of the container with air for a short period after the introduction of the requisite water. It is possible in this manner to discharge a railway tank car thus charged with free flowing particles, flaked or granulated, of caustic soda containing about 65%-85% NaOH in a matter of minutes. Liquid solutions of sufficient concentration for most if not all industrial purposes can thus be formed and the concentration of the solution can be kept below that at which any special difficulties with respect to corrosion are involved. Further, the formation of this solution appears to proceed with sufficient regularity and uniformity to avoid local overconcentrations as well as local overheating within the container in which the solution occurs so that difficulties with respect to corrosion are avoided here as well as in subsequent handling of the caustic soda solution.

In practicing my invention, after concentrating the caustic soda at the point of production to about 65-85% NaOH, I reduce the product to granular or flaked form, I then charge the transportation container with these free flowing particles, and, after delivery of the transportation container, I discharge the container by introducing water into the lower part of the container, advantageously distributed over the lower part of the container, in volume sufficient to form a liquid solution of the desired concentration and running off the resulting liquid solution of the caustic soda. For solutions of concentration approximating 40%-50% for example, the free space within the container originally charged full of the granulated or flaked product is usually sufficient to receive this volume of water, but I may introduce the total volume of water in two or three steps, discharging the liquid solution formed after each successive introduction, particularly to form final solutions of lower concentrations. The required concentration of the caustic soda is economically attained and is attained without any such contamination of the

product as might require special finishing operations. The charging of the transportation container with the flaked or granulated product is simple and expedient. Efficiency with respect to transportation cost is promoted because of the concentration of the product. For many purposes the usual steel containers can be used, and where special protection with respect to metallic contamination is required the ordinary nickel or nickel lined containers or containers protected with the ordinary corrosion resistant coating compositions can be used notwithstanding the concentration prevailing during the actual transportation of the caustic soda. And the discharge of the caustic soda from the container upon delivery in the form of a solution of concentration appropriate for industrial application is simple and expedient and does not require that the transportation equipment be tied up for an unusual time.

To illustrate the industrial application of my invention, I have included a chart in the accompanying drawings which, using 70° F. as a representative initial temperature, graphically indicates (A) the final temperatures attained, and thus the temperature rise, when water sufficient to produce a solution of volume equaling the apparent volume of the solid caustic soda is added in accordance with my invention, (B) the final concentration of the liquid solutions of caustic soda thus produced, (C) and the apparent density of the solid caustic soda prior to the addition of water. This chart constitutes Fig. 1 of the accompanying drawings. The other figures of the accompanying drawings illustrate two forms of railway tank car together with the appropriate equipment for charging and discharging the tank car with caustic soda in accordance with my invention. In the accompanying drawings, Fig. 2 represents a tank car and loading bin in elevation, Fig. 3 represents the same tank car and loading bin in plan and Fig. 4 represents the same tank car and loading bin in end elevation, Fig. 5 represents an end elevation of a modified form of tank car together with a loading bin and Fig. 6 represents a plan of the tank car and loading bin illustrated in Fig. 5.

Referring to Figs. 2, 3 and 4 of the drawings, the tank car 1 illustrated is the conventional railway tank car except for the provision of a plurality of charging ports 8 and a grid of distributing pipes 9 arranged in the lower part of the car tank and connected through a manifold to an external connection 10. The car tank is provided with the usual bottom discharge connection 11. A bin 12 with appropriate connections 13 is disposed to permit charging of the car tank through the several charging ports 8 simultaneously. Conventional apparatus 14 for flaking or granulating the caustic soda may be positioned immediately above this bin 12 in association with appropriate conveying mechanism 15 for distributing the flaked or granulated caustic soda through the bin 12. The several pipes 9 are each provided on their lower side with spaced apertures to distribute the fluids introduced through connection 10 over the lower part of the car tank. The same parts are designated by the same reference characters in Figs. 5 and 6 as in Figs. 2, 3 and 4. The car tank instead of being essentially circular in cross section, however, is extended vertically, as illustrated in Fig. 5. With a car tank of this configuration, increased car loads can be accommodated within established railway

standards notwithstanding the reduced apparent density of the flaked or granulated caustic soda.

In carrying out my invention in the equipment such as that illustrated in Figs. 2 to 6 inclusive, the car tank is charged, at the point of production, with solid caustic soda in the form of free flowing particles containing about 65%-85% NaOH through the connections 13 and the ports 8. The car tank is then sealed and the car put in transit. Upon delivery water is run into the car tank through connection 10 and the distributor pipes 9 in the required volume. For example, the car tank may be substantially filled with the flaked or granulated product and then substantially filled with added water. Or the tank car, somewhat less than full of the flaked or granulated product, may be substantially filled with added water. Or the charged tank car may be filled and drained and again filled and drained in two or more steps. The solid caustic soda dissolves rapidly in the introduced water, but without any substantial local overheating or local overconcentration. To expedite the solution, air may be blown through the contents of the car tank, through connection 10 and the distributor pipes 9, for a few minutes after the requisite water has been added. The resulting liquid solution of the caustic soda is discharged from the car through connection 11.

The amount of water to be introduced to dissolve the flaked or granulated solid caustic is subject to some variation. There is a minimum amount which must be added to dissolve the caustic soda to form a solution liquid at the prevailing temperature. This minimum amount is readily determined by reference to the solubility of caustic soda in water and the concentration of the caustic soda with which the container is charged. Within the range of concentration approximating 65%-85% NaOH, a volume of water sufficient to form a solution in volume approximating the apparent volume of the flaked or granulated solid caustic soda will produce a solution liquid at ordinary atmospheric temperatures. Somewhat smaller quantities of water can be used to produce more concentrated solutions, within the minimum limit above indicated, but sufficient water should be added in any case to avoid concentrations so high as to involve objectionable corrosion of the particular equipment used for shipping and handling the solid caustic soda and the delivered caustic soda solution.

For example, the amount of introduced water may be regulated to produce a liquid solution of caustic soda of 50% NaOH concentration. In this manner my invention can be made available, for example, to former users of 50% NaOH caustic soda solutions without involving any change in the handling of the delivered caustic soda. Working with a prevailing temperature of 70° F., it will be apparent by reference to Fig. 1 of the accompanying drawings that with a flaked solid caustic soda ranging from 65% to 85% NaOH and ranging from about 51 to about 57 pounds per cubic foot in apparent density the introduction of water in volume forming a solution approximately equaling in volume the apparent volume of the solid caustic soda produces a liquid solution of caustic soda ranging from somewhat less than 40% to somewhat more than 50% NaOH concentration. It will be obvious that the flaked or granulated caustic soda in the container and the introduced water need not be at the same temperature, and that the practice of my invention does not depend upon the existence of the

temperature, 70° F., used for purposes of illustration in Fig. 1.

The quantities of water required to form a 50% NaOH solution from a flaked or granulated product of concentrations ranging from 65% to 85% NaOH in accordance with my invention is indicated in the following tabulation. This tabulation also indicates the order of temperature change involved in formation of the solution. It will be noted that the maximum temperature rise is but 100° F. Opposite the per cent NaOH concentration of the flaked or granulated product in the first column, the quantity of water in parts by weight to be added per 100 parts of the flaked or granulated product to form a solution of 50% NaOH concentration appears in the second column and the temperature change (approximate) appears in the third column:

I	II	III
Per cent	Parts	°F.
65	30	-14
70	40	+16
75	50	+45
80	60	+75
85	70	+100

The quantities of water required to form solutions of other concentrations are readily determined by conventional calculations. Temperature rises are higher for solutions of lower concentration, when made from the same strength of flake.

In summary, my invention provides improvements in the transportation of caustic soda which combine several important economic advantages. My invention reduces the cost of transportation by reducing the proportion of water inevitably transported with caustic soda shipped at a concentration of 50% NaOH for example. At the same time, it avoids the disadvantages of shipment of caustic soda in higher concentrations as hitherto practiced. The concentration of caustic soda required in carrying out my invention, concentrations approximating 65%-85% NaOH, are economically attained in conventional apparatus, and without complications with respect to contamination. Caustic soda of 65%-85% NaOH concentration is economically reduced to granular or flaked form in conventional apparatus. This granulated or flaked product is easily handled in connection with loading. The transportation containers can be constructed of conventional materials, and, when required, conventional linings or protective coatings can be used. Protection of the container with respect to high temperatures or high NaOH concentrations is not necessary for many purposes and for most purposes involves no unusual difficulty. The unloading of the containers upon delivery is simple and requires but little time. The solution of the solid caustic soda in the container for delivery does not involve the hazards of local overheating or local overconcentration and does not incur sufficient temperature rise to involve any unusual difficulties with respect to contamination.

My invention will also permit the producer of caustic soda to store it, economically, in the form of a flaked or granulated product of 70%-80% NaOH concentration, for example. Hitherto, most producers of caustic soda have found it necessary to reduce the product to the anhydrous form for storage when storage at the point of production became necessary for any reason.

I claim:

1. In the transportation of caustic soda, the improvement which comprises substantially filling a tank car with solid caustic soda in the form of relatively cool free-flowing particles containing about 65%-85% NaOH, and discharging the tank car by first introducing relatively cool water into the bottom thereof in an amount sufficient to form an aqueous NaOH solution liquid at ordinary atmospheric temperature but insufficient to cause a temperature rise of more than about 100° F. and insufficient to cause the temperature to rise to a value substantially exceeding 147° F., and thereafter without further dilution running off the resultant liquid solution of the caustic 15 soda from the tank car.

2. In the transportation of caustic soda, the improvement which comprises substantially filling a tank car with caustic soda in the form of relatively cool free-flowing particles containing 65%-85% NaOH, and discharging the tank car by first introducing relatively cool water into the bottom thereof in an amount sufficient to form an aqueous solution containing not more than approximately 50% NaOH but insufficient to cause a temperature rise of more than about 100° F. and insufficient to cause the temperature to rise to a value substantially exceeding 147° F., and thereafter without further dilution running off the resultant liquid solution of the caustic 20 soda from the tank car.

3. A method of discharging caustic soda from a container containing a large body of caustic soda originally charged in the form of free flowing particles, said caustic soda having a temperature not substantially exceeding 70° F. and containing not less than about 65% nor more than about 80% NaOH, comprising first introducing water into the bottom of the container in an amount sufficient to form an aqueous NaOH 25 30 35 40

solution liquid at ordinary atmospheric temperature but insufficient to cause the temperature to rise to a value substantially exceeding 145° F., and thereafter without further dilution running off the resultant liquid solution of the caustic soda from the container.

4. In the transportation of caustic soda, the improvement which comprises substantially filling a tank car with solid caustic soda in the form of relatively cool free-flowing particles containing about 65%-85% NaOH and discharging the tank car by introducing relatively cool water into the bottom thereof in an amount sufficient to form an aqueous solution containing less than approximately 50% NaOH but insufficient to cause a temperature rise of more than about 100° F. and insufficient to cause a final temperature substantially exceeding 147° F., blowing the contents of the tank car with air, and thereafter without further dilution running off the resultant liquid solution of caustic soda from the tank car.

5. In the transportation of caustic soda, the improvement which comprises introducing into a large transportation container a substantial body of caustic in the form of free-flowing particles containing not less than about 65% nor substantially more than about 80% NaOH, said caustic having a temperature not substantially exceeding about 70° F., and discharging the caustic by first introducing water at a temperature not substantially exceeding 70° F. into the bottom of the transportation container in an amount sufficient to provide a liquid solution containing less than approximately 50% NaOH but not less than about 40% NaOH, and thereafter without further dilution running off the resultant liquid solution of the caustic soda from the transportation container.

ROBERT BURNS MACMULLIN.
